UNITED STATES PATENT OFFICE.

JAMES W. KENT, OF BROOKLYN, NEW YORK, ASSIGNOR TO KENT MACHINE WORKS, INC., OF BROOKLYN, NEW YORK, A CORPORATION OF NEW YORK.

AGITATING APPARATUS.

Application filed November 30, 1923. Serial No. 677,766.

To all whom it may concern:

Be it known that I, JAMES W. KENT, a citizen of the United States, and resident of Brooklyn, in the county of Kings and State 5 of New York, have invented certain new and useful Improvements in Agitating Apparatus, of which the following is a specification.

In the manufacture of ready mixed paints and other substances it is usual and desirable 10 for purposes of economy and for other well established reasons to provide one mixing machine to stir and thereby mix the contents of a number of separate mixing tanks, the tanks with the proper ingredients therein 15 being successively placed in operative relation to the mixing machine, where their contents are stirred to desired consistency, and successively moved from the mixing machine to another location where cans and 20 other receptacles are filled therefrom for supply to the trade. It is not always feasible, however, to empty the tanks of their contents immediately following movement of the tanks away from the mixing machine 25 after completion of the mixing operation, and as the mixed contents of the tanks soon settle after agitation thereof ceases, the heavier portions of the contents sinking to the bottoms of the tanks and the lighter 30 portions rising to the tops thereof, the result is that the cans or receptacles first filled from a tank that has been allowed to stand some time after the contents thereof have 35 been mixed contains a thick, heavy mixture, while cans or receptacles that are last filled contain a much thinner and lighter mixture, which condition manifestly is extremely undesirable. Accordingly it is my purpose to 40 provide means to maintain the mixed contents of the tanks agitated during the dispensing operation, thereby to assure uniform consistency of the mixture supplied to each can or receptacle.

Tanks of the kind referred to in the foregoing are quite large, having an average capacity of from sixty to one hundred gallons, and it is usual to elevate them by suitable hoisting mechanism to dispose draw-off cocks in their bottoms conveniently above 45 the cans to be filled to facilitate the filling

operation. As in the case of the mixing machine, it is desirable for purposes of economy and other well established reasons to provide a single hoisting mechanism for elevating the tanks, and accordingly it is 55 my further purpose to associate with such a single hoisting mechanism means to facilitate attachment and detachment of the latter to and from the tanks and also to maintain the contents of the tanks agitated while the 60 tanks are suspended and while the contents 65 thereof are being drawn off.

With the foregoing and other purposes in view, my invention consists in the novel features of construction, combination and 70 arrangement of parts, and in the methods I employ to accomplish my purposes, as will be hereinafter more fully described, illustrated in the accompanying drawings and defined in the appended claims. 70

In the drawings:—

Figure 1 is a view in elevation illustrating a primary mixing station and a dispensing station, a tank in operative relation to a mixing machine being shown at the former 75 station and a suspended tank and means to maintain the contents thereof agitated being shown at the latter station;

Figure 2, an enlarged elevation of a tank showing my improved means for attaching 80 hoisting mechanism thereto and for maintaining the contents thereof agitated;

Figure 3, a fragmentary plan view, partly in section of the parts shown in Figure 2;

Figure 4, a detail section on the line 4—4 85 of Figure 2; and

Figure 5, a section on the line 5—5 of Figure 3.

In Figure 1 of the drawings I have illustrated a mixing machine A of conventional 90 design and without novelty consisting essentially of a vertical shaft 10 that is rotatably driven and that is vertically slidably so that it may be raised to permit a tank to be moved into and out of operative relation 95 with the machine, and lowered to dispose mixing blades 11 thereon within a tank that has moved into operative relation with the machine to mix the contents thereof.

Arranged at a suitable dispensing location 100

remote from the mixing machine A is a hoisting mechanism B of any preferred type, the same being herein shown as a conventional block and tackle mechanism, also 5 without novelty.

The tanks C, within which paint or other substances are adapted to be mixed by the machine A, and from which the paint or other substance when mixed is adapted to 10 be dispensed when the tanks are elevated by the hoisting mechanism B, also are of conventional design and without novelty, and are provided as is usual with castor wheels 12 whereby they may readily be moved to 15 desired locations. They are also provided with oppositely disposed straps 13 terminating at their upper ends in hooks 14 to facilitate attachment of hoisting mechanism thereto, and with draw-off cocks 15 in their 20 bottoms through which their mixed contents are delivered into cans and other receptacles for supply to the trade.

The process of producing ready mixed paints and other substances by means of the 25 mixing machine A, hoisting mechanism B and tanks C is apparent and as follows; First, a tank C with the proper ingredients therein, such as pigment and oil, is moved into operative relation with the machine A 30 and shaft 10 of the latter is lowered to submerge the mixing blades 11 thereof within the tank's contents. Rotation then is imparted to the shaft 10 until the contents of 35 the tank have been thoroughly mixed, when rotation of shaft 10 is stopped and said shaft elevated. An attendant then engages a handle member c with lugs on one of the castor brackets on the tank and moves the tank from the mixing machine to a point 40 beneath the hoisting mechanism B, after which the hoisting mechanism is engaged with the tank and the latter elevated, its contents then being dispensed through its draw-off cock 15 into cans and other receptacles for supply to the trade.

After the contents of a tank have been mixed it is not always feasible to dispense them immediately, and unless this is done the cans or containers that are filled for 50 supply to the trade do not, for the reasons previously mentioned, contain a mixture of even consistency. Therefore, I have devised mechanism to maintain the mixed contents of tanks C agitated while said tanks are elevated and during the operation 55 of dispensing their contents, thereby to overcome the difficulty just mentioned, and also to provide a ready means of attaching the hoisting mechanism to and from the 60 tanks.

The mechanism D consists of a channel iron base plate 16 upon which is mounted an electric motor 17 carrying on its drive shaft 18 a worm 19 meshing with a worm wheel 20 on a vertical shaft 21 that extends down-

wardly through said base plate and at its lower end carries suitable agitating blades 22. At its upper end said shaft has bearing in a suitable worm and worm wheel housing 23 that is bolted or otherwise rigidly secured 70 to the base plate.

Rising from the base plate near each end thereof is a pair of supports 24. The supports of each pair being secured respectively to opposite sides of the base plate and 75 being converged with respect to each other towards their upper ends where they are secured to a bar 25 that extends parallel to the base plate above the housing 23 and that has mounted thereon a link 26 with which the block and tackle mechanism B is adapted for detachable engagement. Clamp screws 27 extend through the base plate at the ends thereof whereby said base plate and the mechanism carried thereby 80 may be detachably secured to the tanks C 85 through the instrumentality of the hooks 14 thereon.

After the contents of a tank have been mixed by the machine A and the tank moved beneath the hoisting mechanism B the agitating mechanism D is secured to the tank by the clamp screws 27 and the hoisting mechanism engaged with link 26. The tank then is elevated to a convenient height 90 for dispensing its contents into cans through the draw-off cock 15 in the bottom thereof, and while said tank is elevated the motor 17 is maintained in operation to rotate shaft 10 and thus cause the blades 22 to maintain 95 the contents of the tank agitated whereby the mixture supplied to each can or receptacle is of the same consistency.

I claim;

1. In apparatus of the class described, a 100 suspended stirring mechanism, means for elevating and lowering said mechanism in suspension, and means for detachably and operatively connecting the mechanism to a dispensing tank whereby the tank and mechanism may be elevated in operative union 105 to facilitate dispensing and effect stirring of the tank's contents during dispensing.

2. In apparatus of the class described, a 110 block and tackle suspended from a support, a stirring mechanism supported in suspension by said block and tackle whereby said stirring mechanism may be supported at different elevations, and means for detachably and operatively connecting said stirring mechanism to a dispensing tank whereby the tank and said mechanism may be elevated in operative union to facilitate dispensing and effect stirring of the tank's contents during dispensing.

3. In apparatus of the class described, a 115 block and tackle suspended from a support, a stirring mechanism supported in suspension by said block and tackle whereby said stirring mechanism may be supported at 120 125 130

different elevations, means for detachably and operatively connecting said stirring mechanism to a dispensing tank whereby the tank and said mechanism may be elevated in operative union to facilitate dispensing and effect stirring of the tank contents during dispensing, said stirring mechanism including a base plate, a frame ris- ing therefrom to which said block and tackle is secured, a shaft carrying agitating blades 15 that extend into the contents of the tank when the mechanism is secured to the tank, and a motor for driving said shaft.

In testimony whereof I affix my signature.

JAMES W. KENT.
